COFFEE MAKER

Harold Bloomfield, Chicago, Ill., assignor to Bloomfield Industries, Inc., Chicago, Ill., a corporation of Illinois

Filed Nov. 16, 1964, Ser. No. 82,636

Term of patent 14 years

(Cl. D2—3)

FIG. 1 is a side elevational view of a coffee maker, embodying my new design;

FIG. 2 is a front elevational view thereof;

FIG. 3 is a rear elevational view thereof;

FIG. 4 is a top plan view thereof;

FIG. 5 is a view taken on line 5—5 of FIG. 2, parts thereof being shown in section;

FIG. 6 is a view taken on line 6—6 of FIG. 2, parts thereof being shown in section; and

FIG. 7 is a front elevational view of the upper portion of the upright support with the upper bowl member removed.

I claim:

The ornamental design for a coffee maker, substantially as shown.
